UNITED STATES PATENT OFFICE.

AXEL G. GULBRANSEN, OF CHICAGO, ILLINOIS, ASSIGNOR TO GULBRANSEN-DICKINSON COMPANY, OF CHICAGO, ILLINOIS, A CORPORATION OF ILLINOIS.

AUTOMATICALLY-OPERATED PIANO.

1,078,673.

Specification of Letters Patent. Patented Nov. 18, 1913.

Application filed May 3, 1910. Serial No. 559,125.

To all whom it may concern:

Be it known that I, AXEL G. GULBRANSEN, a citizen of the United States, residing at Chicago, in the county of Cook and State 5 of Illinois, have invented a certain new and useful Improvement in Automatically-Operated Pianos, of which the following is a full, clear, concise, and exact description, reference being had to the accompanying 10 drawings, forming a part of this specification.

My invention relates to automatically operated pianos, and is directed toward improved means for supporting the automatic 15 action mechanism within the casing of an ordinary piano so that it may be properly associated with the keys for the purposes of operating them precisely as if they were operated manually in the usual manner.

It is well known that in automatic piano actions which are operated pneumatically, a "channel board" is provided which extends the length of the piano at the front thereof and has a multitude of "pneumatics" secured to the rear thereof and directly associated with the abstracts of the piano action proper. These channel boards are made of wood and are provided with vacuum chambers and air passages of different kinds, depending upon the precise nature of the pneumatic system employed.

It is the specific object of my invention to provide means for properly mounting this channel board.

As is probably well known in the art and as will presently be evident, these channel boards are not very wide relative to their length and they are subject to warping, often to such an extent as to make their 40 proper disposition in the piano casing a serious difficulty. My invention is effective in providing an arrangement whereby this warping may be met and overcome, and whereby the channel board may be properly 45 adjusted in position.

It is the further object of my invention that this supporting and adjusting means be universal in its application to the many kinds of pianos on the market, and, with 50 this end in view, I have provided means whereby the range of adjustment is of very considerable scope.

My invention is embodied in the struc-

ture illustrated in the accompanying drawings in which,

55

Figure 1 is a front elevational view of the piano with the upper front panel and the keyboard cover removed; Fig. 2 is a fragmentary end view of the parts with which my invention is particularly concerned; Fig. 3 is a plan view on an enlarged scale of one of the elements of the supporting structure of my invention; Fig. 4 is a front view, on an enlarged scale, of two other elements of my supporting structure, 60 and Fig. 5 is an end view of the parts shown in Fig. 4.

65

Like reference numerals are applied to the same parts throughout the various figures.

70

The piano casing is shown at 6, the keyboard being indicated at 7. Those parts with which my invention is not concerned have been omitted for the purposes of clearness in illustration. The music roll box is 75 shown at 8, the air motor at 9 and the pedals for operating the automatic playing mechanism are indicated at 10. It will be understood that the piano proper is of any ordinary and well known construction and that 80 the parts 8, 9, 10 and the associated elements are merely inserted therein and properly connected with the hammers of a piano action.

The channel board of the automatic sys- 85 tem is indicated at 11, and it is with the proper mounting of this channel board that my invention is concerned. The back board of the piano, upon which the strings are mounted, is indicated at 12, and is held in 90 the piano casing by means of suitable bolts 13, 13. A number of pneumatics 11^a are secured to the rear of the channel board and the movable element of each pneumatic is arranged to engage an abstract rod 7^a op- 95 eratively associated with a corresponding key 7^b. The bed of the piano, which is below the keyboard, is indicated at 14, and between this bed and the back board 12 there

are mounted the supporting brackets 15, 15, 100 of which there are usually three or four. One end of each of these brackets is serrated at 16 so that it can be driven in the bed 14 as indicated in the drawings, while the other end is bifurcated, as indicated at 17, for 105 the reception of a bolt 18 which is effective

in securing the other end of the bracket to the back beard, as clearly illustrated. Extending across and secured upon the brackets 15, 15, are various rails and other parts 5 for the proper mounting of the hammers and the associated mechanisms. For instance, one of these rails is indicated at 19. The movable hammer rail, upon which the hammers rest and which is moved by manipulating one of the pedals 20 to moderate 10 the tone, is indicated at 21.

As clearly shown in the drawings, the channel board 11 extends between the side pieces 22, 22 of the easing and is mounted 15 above and to the rear of the keyboard 7. This channel board is primarily secured in place by means of the screws 23, 23, which pass transversely therethrough and which enter the cleats 24, 24 secured, by means 20 of screws 25, 25, to the side pieces 22, 22, as indicated. It is thus clear that the channel board 11 is mounted quite in the manner of a bridge and that, being wood, it is subject to warping which may prove to be very 25 considerable and very detrimental. In addition to this support upon the cleats, as just described, the channel board 11 rests upon a series of screws 26, 26, preferably wood screws, engaging in the bed 14, as 30 clearly shown in Figs. 2 and 5 in particular.

This arrangement of screws is particularly advantageous in first placing the board in position, before employing the screws 23, 23, for it is clear that the screws can be manipulated 35 to raise their common plane or lower it as the occasion requires, particularly as to the relation between the pneumatics carried by the board and the abstracts of the piano.

40 Secured to the front of the channel board 11, at some point intermediate its ends, is a forwardly extending screw-threaded rod 27, rigid adjustment being obtained by means of a flange 28, either integral therewith or secured thereto, through which flange pass the screws 29, 29 which take 45 into the board 11. The screw-threaded rod 27 is adapted to pass through a notch at the end of a head 30 of the pin 31, which 50 extends upwardly from the bed 14, as clearly shown in Fig. 5. This pin may be screw-threaded so as to take into the bed in that way or it may be merely serrated so that it may have proper engagement therein if 55 merely driven into place. Upon each side of the head 30 of the pin 31 a nut 32 is provided and it is clear that the head part may be rigidly clamped between these nuts. It is further clear that these nuts may be 60 manipulated to move the board 11, or at least that part of it forward or back, as desired. And it is clear that more than one of these adjusting elements, comprising the parts 27, 31 and 32, may be provided.

In fact, in Fig. 1, two such elements are 65 shown.

Operating to supplement the adjusting elements which have just been described is a further adjusting element, shown in detail in Fig. 3. Extending from one or more of the brackets 15 is a stud 33, which may conveniently be screwed therein, and to this stud is pivoted, by means of a pivot pin 34, a forwardly extending rod 35, the forward end of which is screw-threaded, as indicated 75 at 36. This rod, as is evident, is adapted to swing about the pivot 34 and is arranged to enter a notch 37 in the top of the board 11 and to receive a nut 38 on each side of the board, as clearly shown in the figure 80 just referred to. It is apparent that here also can the nuts be manipulated to bring that part of the board backward or forward, since the part 15 is absolutely stationary. Thus, after the necessary position of the channel board has been determined, the cleats 24, 24 are put into place and the screws 26, 26 adjusted by the cut-and-try method until their common plane is brought into the proper height so that the 90 channel board resting thereon may be properly associated with the parts to the rear thereof. When brought into place the screws 23, 23 may be tightened and the board is then rigidly secured in place. The 95 pins 31, 31 are, of course, properly disposed so that when the channel board is put into place, the rods 27, 27 extending forwardly therefrom will enter the notches in the heads of the pins. Similarly, the rods 100 35, 35 are pivoted at the proper point so that when they are swung downwardly they may enter the notches provided therefor in the parts, as has just been described. The nuts 32, 32 and the nuts 38, 38 may then 105 be manipulated to bring the board into proper position, to overcome any warping that may have occurred and to securely lock the board against responding to any bending strain that might, in any way, be applied thereto.

I claim as new and desire to secure by Letters Patent:

1. In an automatically playing piano, in combination, a framework, a channel board, 115 means for supporting said board by securing it at its ends to the piano framework, screw threaded posts intermediate its ends for adjusting the position of the board, bifurcated posts on the framework through 120 which said first named posts may pass, and nuts on said first named posts associated with said second named posts.

2. In an automatically playing piano, in combination, a channel board carrying pneumatic action mechanisms for association with the hammers of the piano, a screw-threaded rod pivoted upon an axis sub-

stantially parallel to the board stationary relative to the piano framework, said board having an opening to receive said rod, and a nut on said rod on each side of said board.

5 3. In an automatically playing piano, in combination, a framework, cleats secured to the side pieces of the framework, a plurality of adjustable flat-headed screws secured in the bed of the framework between 10 said side pieces, and a channel board with a flat-bottom resting face to face upon the heads of said screws, said board being secured to said cleats.

4. In an automatically playing piano, in 15 combination, a plurality of adjustable screws secured in the piano framework, a channel board resting on said screws so as to be capable of movement thereon, a screw-threaded rod secured thereto and extending 20 forwardly therefrom, a member rigid with the framework and having a notch therein through which said rod passes, and a nut on said rod on each side of said members.

25 5. In an automatically playing piano, in combination, a channel board, a screw-threaded rod extending therefrom, a member rigid with the piano casing and having a notch through which said rod passes, a nut on said rod on each side of said member, 30 a screw-threaded rod pivoted upon an axis

stationary relative to the piano framework, said board having a notch to receive said rod, and a nut on said rod on each side of said board.

35

6. In an automatically playing piano, in combination, a piano casing, a channel board carrying pneumatic action mechanisms for association with the hammers of the piano, a screw threaded rod extending forwardly 40 therefrom, intermediate of the ends thereof, a member rigid with the piano casing and having an opening through which the screw-threaded part of said rod passes, and a nut on the screw threaded part of said rod on 45 each side of said member.

7. In an automatically playing piano, in combination, a channel board carrying pneumatic action mechanisms for association with the hammers of the piano, a screw 50 threaded rod pivoted on an axis stationary relative to the piano framework, said board having an open notch to receive said rod, and a nut on said rod on each side of said board.

55

In witness whereof, I hereunto subscribe my name this 30th day of April, 1910.

AXEL G. GULBRANSEN.
